UNITED STATES PATENT OFFICE.

KARL A. SIMMON, OF EDGEWOOD PARK, AND HARRY R. MEYER, OF WILKINSBURG, PENNSYLVANIA, ASSIGNEES TO WESTINGHOUSE ELECTRIC & MANUFACTURING COMPANY, A CORPORATION OF PENNSYLVANIA.

CONTROL APPARATUS.

Application filed March 19, 1919. Serial No. 283,474.

To all whom it may concern:

Be it known that we, KARL A. SIMMON, a citizen of the United States, and a resident of Edgewood Park, in the county of Allegheny and State of Pennsylvania, and HARRY R. MEYER, a citizen of the United States, and a resident of Wilkinsburg, in the county of Allegheny and State of Pennsylvania, have invented a new and useful Improvement in Control Apparatus, of which the following is a specification.

Our invention relates to control apparatus for electric motors and especially to foot-controlled devices.

15 In the operation of an electric controller, through the agency of a pedal, or the like, that is actuated by an operator's foot, it is permissible and desirable to provide convenient means so located with respect to the 20 positions of the pedal as to allow the operator to rest his foot without further actuating the controller. It is one object of our invention, therefore, to provide simple and reliable foot-rests for the purpose mentioned.

25 Another object of our invention is to provide means, comprising an adjustable locking member, for retaining the foot-operated controller in a predetermined position when the motorman transfers his operating station from one end of the vehicle to the other.

30 Other minor objects of our invention will become evident from the following description, taken in conjunction with the accompanying drawings wherein—

35 Figure 1 is a plan view of an apparatus, of the type mentioned, that is constructed in accordance with our invention.

Fig. 2 is an end view and Fig. 3 is a view, in elevation, thereof.

40 Fig. 4 and Fig. 5 are views, in end and in side elevation, respectively, of certain portions of the apparatus shown in preceding figures.

45 Fig. 6 is an enlarged view partially in elevation and partially in section, of another portion of the apparatus shown in the previous figures.

Fig. 7 is a sectional view, taken on the line VII—VII of Fig. 6.

50 Fig. 8 is an enlarged view, in end elevation, of another portion of the control apparatus.

Referring to the drawings, the apparatus shown comprises a suitably encased electric controller 1; a foot-actuated device 2 for

the controller; and a latching or locking device 3 that is employed under conditions to be set forth.

The controller 1 is preferably of the familiar drum type, being mounted upon a centrally located shaft 4 and having a suitably configured contact segment 5 and a plurality of co-operating control fingers 6 for effecting the desired circuit connections, as will be understood. In the present instance, the controller is adapted to concurrently govern both the electric circuits and the braking apparatus, as fully set forth in our copending application, Serial No. 302,813, filed June 9, 1919. Consequently, the five operative positions of the illustrated controller are marked "Emergency" which is the normal position to which the device is biased, through the action of a suitable spring 7; "Service" and "Lap", reference being had to the corresponding manipulation of the familiar air-brake apparatus; and "Coast" and "Run", corresponding to the coasting and operating conditions of the vehicle-propelling motors.

The foot-actuated apparatus 2 comprises a suitably formed pedal 10 which the operator's foot may conveniently engage; and a dog or support 11, which is rigidly secured to the controller shaft 4 by means of a setscrew 12, for the purpose of detachably supporting the pedal 10. A downwardly-extending lug or arm 13 of the dog 11 is provided with a horizontally-located aperture 14, for a locking purpose to be set forth.

A plurality of foot-rests or stops 15 and 16 are located as near as possible to the pedal 10 and, as clearly shown in Fig. 4 and Fig. 5, are so shaped as to conform to the angular position of the pedal when the controller occupies the "Lap" and the "Coast" positions, respectively. Since it may be necessary for the operator to maintain his foot for some time in the positions corresponding to "Lap" or "Coast" operation of the vehicle, a considerable hardship would be imposed upon him were it not for the provision of the illustrated foot-rests. These rests or stops 15 and 16 may conveniently be formed of a single casting, as shown, or of hard-wood blocks, respectively having sloping upper surfaces 17 and 18 that extend in directions parallel to the dotted lines marked "Lap" and "Coast", the outer

sides of the foot-rests 15 and 16 constituting suitable ridges or barriers 19 and 20 for preventing the toe of the operator from slipping, or from entirely leaving the 5 pedal 10.

It will be seen that the illustrated foot-rests permit the operator to shift his weight into a more comfortable position without entailing any further actuation whatsoever 10 of the controller. The foot-rests do not interfere, in any way, with the normal operation of the pedal, but are so located as to conveniently permit the toe of the operator to slide upon them when desired.

15 Referring to the enlarged view, Fig. 8, the pedal 10 is shown as comprising a flat heel plate 21 and a raised and suitably curved toe plate 22, this form of pedal being the most convenient and reliable for actuation by foot power. A plurality of depending lugs or ribs 23 and 24 are wedged into corresponding slots or grooves in the upper side of the dog or support 11, whereby the 20 pedal is normally held in position with a firm grip, but may be readily removed when the operator changes his station from one end of the vehicle to the other. In this way, only one pedal is required for double-end 25 operation of a vehicle and, furthermore, unauthorized manipulation of the control apparatus by passengers upon the rear end of the vehicle is prevented.

As is customary in double-end operation 30 of a vehicle, the corresponding electrical circuits of the two car-controllers are connected in parallel relation to permit complete operation of the car-propelling motors from either operating station. In the present instance, however, if either controller were 35 left in its normal or biased position "Emergency," the car circuits would be so energized that emergency operation of the air-brakes would be effected, regardless of the operation of the controller at the other end 40 of the vehicle. Consequently, we have provided a simple and effective latching or retaining device 3 for maintaining the controller preferably in its "Lap" position, whenever the operator "changes ends."

45 The latching device 3, most clearly shown in Fig. 6, comprises a suitable pillow-block or bearing member 30 upon which is mounted a small journal or bearing member 31 for one end of the controller shaft 4, a spacing 50 collar or sleeve 32 being integrally or otherwise related to the pillow-block proper.

55 A milled knob or handle member 33 is provided with a rib or lug 34 upon its inner face, for the purpose of engaging a corresponding slot or groove in the collar 32, when the knob occupies a certain position. Rigidly secured to the knob 33 and extending in alinement with the aperture 14 of the 60 pedal dog 11 is a pin or small rod 35, which 65 is surrounded by a helical biasing spring

36 that acts between an internal surface of the spacing collar 32 and a small washer or retaining collar 38 that is located intermediate the ends of the pin 35.

As will be evident from the illustrated 70 structure, whenever the knob 33 is manually adjusted in a position corresponding to the registration of the rib 34 and the corresponding slot, then the pin 35 protrudes beyond the pillow-block 30 and enters the aperture 75 14 of the pedal-dog lug 13, provided that the dog occupies a position corresponding to the "Lap" position of the controller. Under such conditions, the controller is firmly 80 locked in the desired position and the pedal 10 may be removed to the other end of the vehicle without fear of unauthorized actuation 85 of the controller upon the rear end of the car.

Under normal operating conditions, however, that is, when the illustrated controller is to be actively employed, the knob 33 is turned into some position wherein the rib 34 extends transversely of the corresponding slot. In this case, the pin 35 is entirely 90 withdrawn from the aperture 14 of the pedal dog and, consequently, unimpeded actuation 95 of the pedal 10, in accordance with the desires of the car operator, is permitted.

We do not wish to be restricted to the 95 specific structural details or arrangement of parts herein set forth, as various modifications thereof may be made without departing from the spirit and scope of our invention. We desire, therefore, that only such 100 limitations shall be imposed as are indicated in the appended claims.

We claim as our invention:—

1. The combination with a member adapted to assume a plurality of definite positions when actuated by an operator's foot, of a plurality of foot-rests respectively shaped to conform to the angular positions of said member, whereby the operator may rest his foot without further actuating said member. 105

2. The combination with a pedal adapted to assume a plurality of definite positions when actuated by an operator's foot, of a plurality of foot-rests located on opposite sides of said pedal and respectively shaped to conform to the angular positions thereof, whereby the operator may slide his foot on said foot-rests without further actuating the pedal. 110

3. The combination with a plural-position controller, of a pedal for actuating said controller through its positions, a plurality of foot-rests located on opposite sides of said pedal and respectively corresponding to said positions to permit the operator to shift his weight without further actuating the controller. 115

4. In a device of the character described, in combination, a manually operable member disposed for movement into a plurality 120 125 130

of predetermined positions, means adapted to retain said member in any of said predetermined positions, and a plurality of rests disposed to correspond to the different predetermined positions of said manually operable member.

5. In a device of the character described, in combination, a manually operable member disposed for movement into a plurality of predetermined positions, said member being adapted to receive an operator's foot, means adapted to retain said member in any 10 of said predetermined positions and a plu-

rality of rests disposed to correspond to the different predetermined positions of said 15 manually operable member, said rests having an angular inclination corresponding to said foot-receiving member as said manually operable member is moved to different 20 positions.

In testimony whereof we have hereunto subscribed our names this 11th day of March, 1919.

KARL A. SIMMON.
HARRY R. MEYER.
